UNITED STATES PATENT OFFICE.

HARRY WILKINS, OF EVANSVILLE, INDIANA, ASSIGNOR OF ONE-FOURTH TO WILLIAM H. REDMAN, ONE-FOURTH TO WILLIAM M. SMITH, AND ONE-HALF TO JAMES P. WILSON, ALL OF VANDERBURG COUNTY, INDIANA.

TRAIN-CONTROLLED ELECTRIC RECORDING CROSSING-SIGNAL.

1,155,535.

Specification of Letters Patent.

Patented Oct. 5, 1915.

Application filed November 29, 1912. Serial No. 734,223.

To all whom it may concern:

Be it known that I, HARRY WILKINS, a citizen of the United States, residing at Evansville, county of Vanderburg, and State of Indiana, have invented certain new and useful Improvements in Train-Controlled Electric Recording Crossing-Signals, of which the following is a specification.

This invention relates to train controlled electric recording crossing signals.

My object is to provide a visual crossing signal adapted for electrical operation by an approaching train at a distance wherein improved means will be provided for operating the signal, preferably a semaphore arm and also for automatically recording the operation of the signal and the time it is operated, thereby maintaining a record of the different operations which will constitute proof that at certain times the signal operated.

Another object is to provide an improved track instrument adapted to be actuated by a train, for the control of the electrical circuit by which a visual crossing signal is operated.

Another object is the provision of a visual crossing signal and an improved operating mechanism for wigwagging said signal.

A further object is the provision of an improved recording mechanism for crossing signals.

The invention is set forth fully hereinafter and the improved and novel features are recited in the appended claims.

In the accompanying drawings:—Figure 1 is a plan view of the signal and a part of a railroad track; Fig. 2, a detail side elevation of one of the track instruments; Fig. 3, a detail of the recording dial or disk; Fig. 4, a detail of a disk used in connection with the punch pin; Fig. 5, a vertical section of the signal; and Fig. 6, a plan view of the signal operating and recording mechanism.

The track instruments 1 and 2 are disposed at any desired distance from the crossing and are adapted to be struck by the wheels of a passing train. These track instruments consist of a base 3 to which is secured or with which is formed integrally the arms 4 and 5. Pivoted at 6 to the base is a trip 7 which in turn has pivoted thereto at 8, plungers 9 and 10 which are cushioned on springs 11 in dash-pots 12 and 13 on the

arms 4 and 5. The trip 7 is thus rendered self-restoring and is adapted to maintain an upright position when not depressed by a train as the springs 11 are of the same strength and mutually coöperate with the trip 7 to maintain it in substantially vertical position so that it may be struck by a train traveling in either direction. The trip is provided with a contact block 14 which is adapted to be brought into engagement with contacts 15 and 16 of the circuit 17 which controls the signal, the said contacts 15 and 16 being carried by any suitable insulating head 18 carried by base or plate 3. When the trip 7 is struck by a train traveling away from the crossing, the direction of movement throws the contact block 14 away from the contacts 15 and 16 and the circuit is, therefore, not completed, but when the train is approaching the crossing, the trip is so struck that the contact block 14 is pressed against the contacts 15 and 16 and the circuit is completed and the signal operated. The contacts 14, 15 and 16 may be made movable or cushioned in any desired manner to compensate for the shock of their engagement.

The electrical conductors may be suitably inclosed in a conduit or pipe 19.

At or near the crossing in some suitable position is located the base 20 of the signal, above which is the box or housing 21 and the staff or pillar 22, the latter being surmounted by a signal light 23 of any preferred form. The column 22 is hollow and provided with a box-like head 24 having an open side 25 in which is pivoted at 26 a signal or semaphore 27 which is adapted to be wigwagged up and down. To that end, there is provided an arm 28 connected to the semaphore, this arm in turn being pivoted to a link 29. Pivoted at 30 to the link 29 is a plunger 31 which slides through guides 32 and 33 fixed in the staff 22 and extends loosely down through the bottom 34 of the said staff, the lower end thereof being preferably beveled at 35. Secured to the plunger 31 is a disk or head 36 and interposed between this disk and the guide 33 is a coil spring 37 which, by bearing on the disk or collar 36, tends to throw the signal or semaphore 27 into horizontal position. A cushion, preferably of rubber 38, loosely surrounds the plunger 31 below the collar 36.

and takes up the shock or impact of the said collar under the tension of the spring.

Journalized in suitable bearings in the box or base 21 is a shaft 39 which carries a gear 40 and a cam 41 having a grooved periphery. The beveled end 35 rests on the grooved periphery of the cam 41, such grooved periphery preventing lateral displacement of said end 35 and insuring its maintenance in contact with the cam at all times. Any suitable electric motor 42, which is secured on base 20, drives the gear 40 through a pinion 43 in mesh therewith, said electric motor being included in the circuit 17. Any suitable source of electrical current may be employed for the circuit 17 which is opened and closed by the track instruments 1 and 2, but always remains open except when a trip is struck by a train approaching a crossing. Consequently, the semaphore 27 remains stationary except when a trip is struck by the train. On the gear 40 is a tappet 44. Pivotaly mounted on a bracket 45 is a hammer 46 which has a beveled end 47 adapted to be engaged by the tappet 44 once during each revolution of the gear 40, a spring 48 normally maintaining the end 47 in position to be struck by the said tappet. Suitably mounted in line with the head of the hammer 46 is a spring-retracted punch pin 49 which is adapted to be struck by the hammer when the latter is engaged by the tappet 44. The point of the punch pin operates through a hole 50 in a disk 51 secured to a bracket 51^a. Driven by an hour arbor of any suitable clock movement 52 contained within box 21 is a disk 53 to the face of which is secured a cork disk 54. The disk 54 rotates with the disk 53 and is adapted to serve as a cushion and carrier for a paper recording disk or dial 55 bearing the hours, similar to a clock dial and provided with a blank rim 56 concentric with the dial part thereof. The recording disks or dials 55 are intended to be supplied each day to the dials 53 and 54 or twice a day if the hours thereon are only numbered from 1 to 12. The disk 51 assists in holding disk 55 but does not rotate with it.

Assuming that a dial 55 has been secured to the disk 54 with the hours thereon so arranged in relation to the punch pin 49 as to represent the hour at which the dial is placed on the disk 54 and, subsequently, either of the trips 7 is struck by a passing train, the hour of the day is then opposite the punch pin 49, due to the rotation of the hour arbor of the clock movement. The circuit being closed through the contacts 14, 15 and 16, the electric motor 42 is operated and the gear 40 turned with the cam 41, causing the semaphore 27 to wigwag up and down and attract the attention of those who are about to go over the crossing. Once during each revolution of the gear 40, the

tappet 44 strikes the beveled end 47 of the hammer 46 and causes the latter to deliver a blow onto the punch pin 49, the latter striking the margin 56 of the record dial 55 and making a perforation therein. Perforations will be made in the dial 55 corresponding to the number of revolutions of the gear 40, which in turn is dependent on the period of energization of the motor 42 and that, again, being dependent on the length of time the trip 7 is depressed, indicating the period of time the train occupied in passing the crossing. The wheels of a train strike the trip 7 in such rapid succession that the contacts 14, 15 and 16 remain closed until the train has completely passed the trip, and consequently, as long as the train is passing over the trip 7, the motor 42 continues its rotation. Each time the cam 41 rotates, the signal arm is wigwagged one time and the tappet 44 actuates the hammer 46 once, thus striking the punch pin 49 once against the disk 56, thus making one pin punch on the dial. The pin punches or marks are repeated, in succession on the dial 55 as it is turned by the clock movement, while the train is passing over the trip 7.

The dial is preferably of a sufficiently large size, say twelve inches or more in diameter, to afford the requisite space for indication of the succession of dots. For instance, with a twelve inch dial 56, if the clock dial moves one-sixteenth of an inch, the twelve inch dial would move about one-quarter of an inch, thereby affording plenty of space for the succession of punch marks made while the train is passing over the trip.

If desired, a light or lantern of any kind can be provided on the semaphore 27 or arranged to be operated by it so that the signal is clearly visible at night.

The provision of the recording apparatus insures the keeping of an accurate record of the operation of the signal and is useful in case of a dispute as to whether the signal operated at a given hour on a given day, as the dials 55 will be dated and filed away for future reference.

Having thus described my invention, what I claim as new and desire to secure by Letters Patent, is:—

1. In a train controlled recording crossing signal for railways, the combination with a wheel, of a hammer adapted to be periodically operated by said wheel, a marking device adapted to be operated by the hammer, a clock-operated record adapted to receive the markings of the marking device, and track instruments located on opposite sides of the crossing and for actuation by the train, said track instruments controlling the rotation of the wheel.

2. In a train controlled recording crossing signal for railways, the combination with an

electric motor, a wheel driven thereby, a hammer, means operated by the wheel adapted to periodically operate the hammer, a marking device adapted to be operated by the hammer, a clock-operated record adapted to receive the markings of the marking device, track instruments on opposite sides of the crossing which are adapted for actuation by a train, and electrical circuit con-

nnections for the electric motor which are controlled by said track instruments.

In testimony whereof, I hereunto affix my signature in presence of two witnesses.

HARRY WILKINS.
